United States Patent

Des. 240,909

Patented Aug. 10, 1976

240,909

AIRPLANE

Philip C. Whitener, Seattle, Wash., assignor to
The Boeing Company, Seattle, Wash.

Filed Nov. 29, 1974, Ser. No. 528,172

Term of patent 14 years

Int. Cl. D12—07

U.S. Cl. D12—76

*Fig. 2**Fig. 3**Fig. 4**Fig. 5*FIG. 1, is a perspective view of the new airplane design; FIGS. 2, 3 and 4 are a plan view, a front elevation and a side elevation, respectively; and

FIG. 5 is a plan view showing a modification of the design which differs from the configuration shown in FIGS. 1 through 4 only in the respects shown in this figure.

What is claimed is:

The ornamental design for an airplane, as shown and described.
